UNITED STATES PATENT OFFICE.

GEORGE EUGENE MITTINGER, OF CLEVELAND, OHIO.

METAL KEG.

Application filed October 22, 1923. Serial No. 670,035.

This invention relates to improvements in metal kegs, and more particularly to what I have termed a knock-down or sectional container, which is primarily adapted for 5 transporting bolts, rivets, nails or the like, although the container could be easily and readily used as a transporting means for most any commodity.

At the present time, the ordinary wooden 10 keg is the container which is most used in shipping commodities of different characters, but a wooden keg has many disadvantages which are well known to those coming in constant contact with their use. The wooden 15 keg is expensive and difficult to assemble and when it has reached its destination, many of its contents have been lost due to the fact that the side of the keg has been broken or the head of the keg has not remained intact.

20 My improved container has overcome the above disadvantages of the wooden container. The parts for my container are fabricated very rapidly by machine, the container parts are assembled very rapidly due to their 25 particular and peculiar construction, and the container is very strong and, in every instance, reaches its destination in good condition with its contents intact. My container is of such strength that when loaded with 30 two hundred pounds of commodity, it can be dropped, at least, ten feet without bursting either its sides or heads. The advantage of a container of this strength will be readily apparent.

35 I am very familiar with the fabrication of metallic containers and have invented and fabricated containers of many different constructions. Some of the containers have been patented by me, while others are at the 40 present time in the process of being patented and are now pending in the Patent Office.

For a sectional metal container to be a commercial success, it must be so constructed that its several parts can be rapidly and 45 cheaply fabricated by machine. The several parts of the container must be so constructed that the complete container can be rapidly and easily assembled. The assembled container must be of a construction that is very strong 50 both as to its side-walls and side-wall joints and as to the fastening in of the container heads. Another important attribute of the container is that it must be so construed that during the handling of the container, from 55 the time it is assembled to the time it reaches its destination, there must be no sharp edges

on which persons can cut or mutilate their hands. I have found that the commercial success of containers has been lost for the simple reason that in handling the containers persons have cut and mutilated their hands badly and, in some instances, blood poison has set in. It is impossible to market a container with such a serious weakness or drawback as that just mentioned.

60 The container which will be hereinafter described and claimed and which is shown in the accompanying drawings, overcomes all the above objections and incorporates in one container many advantages and novel features of construction.

65 At this point it might be well to mention that where a container is entirely assembled with the exception of one of the heads, that in many instances it will be sprung out of 70 shape as the container is filled with heavy material and that due to this springing of the container, it will be impossible to put the head on the same to close it after it has been filled.

75 As the containers are shipped to the consumer, in a knockdown or unassembled state, it is essential that the parts can be placed in nested relation to reduce the space that they will consume in a freight car, or the like, so 80 that tonnage can be shipped in the car. If tonnage cannot be gotten into the car, the freight rate would be a very large item of expense in placing the container in the hands of the consumer. In fact, the freight rate 85 would be so high that the metallic container could hardly be marketed in competition with wooden containers.

90 The primary object of my invention is to provide a metallic barrel or keg having a 95 plurality of sections adapted to be assembled in the form of a complete container.

95 Another object of my invention is to provide a barrel or keg made in a plurality of sections and adapted to be unassembled so 100 that the sections can be readily nested or stacked, whereby a vast amount of space is saved in transportation of the empty containers and tonnage can be packed in a freight car, or the like.

105 A further object of my invention is to provide a collapsible container having a novel means for holding it in its assembled form.

110 Another and further object of my invention is to provide a sectional container so constructed as to overcome the springing or

wrenching out of its normal shape during the process of filling or loading it.

A still further object of my invention is to provide a container of the character described, in which the heads are readily secured upon the container and more securely locks the container side sections together and prevents them from being collapsed.

Another and further object of my invention is to provide a sectional container so constructed and designed that there are no sharp cutting edges which will be likely to injure the hands of the persons assembling the container or handling the container at any time during its loading or shipment.

A further object of my invention is to provide a sectional container which can be readily assembled or unassembled and which in its assembled form is very strong.

Another object of my invention is to provide a sectional metallic keg which is cheap and simple of manufacture, highly efficient in use and having certain novel details of construction which will be hereinafter more fully pointed out and described.

In the drawings:

Figure 1 is a perspective view of my improved container in its unassembled form ready for shipment, a portion of the head and upper end of the container being broken away and shown in vertical section.

Fig. 2 is a perspective view of one of the container side-wall sections.

Fig. 3 is a horizontal sectional view taken through the assembled container.

Fig. 4 is an enlarged fragmentary horizontal sectional view, showing the interlocking connection of the container sections, before the container head is locked in place.

Fig. 5 is an enlarged fragmentary horizontal sectional view of the interlocking edges of the sections with the container head locked in place.

Fig. 6 is an enlarged fragmentary vertical sectional view of the interlocking edges of the container sections with the container head in place.

Fig. 7 is a fragmentary vertical sectional view of the upper ends of the container taken at a point beyond the interlocking edges of the sections, the container head being shown locked in place.

Fig. 8 is an enlarged fragmentary side view of a portion of one of the container sections showing the manner in which the horizontal corrugations of the container sections and at the interlocking edge of the section.

Fig. 9 is an enlarged fragmentary horizontal view showing a modified form of locking the container head in place.

Fig. 10, is a side view partially broken away in vertical section, showing the manner in which the container heads stack for shipment.

Fig. 11 is an end view showing the man-

ner in which the container sections are stacked for shipment.

Referring now to the drawings, I have designated the container sections which compose the side walls of my container, as A, and the container end or heads as B. Each of the barrel sections A is semi-circular in form, as clearly appears in the drawings, and constitute, when assembled, a round hollow cylinder. The container heads B are composed of one piece and when locked in position upon the ends of the container sections entirely close them.

In the drawings, I have shown the container body as composed of two sections, but it will be readily understood that the same can be constructed in as many sections as may be desired without departing from the spirit of this invention. I have found, however, that a barrel constructed with two sections is preferable, as it will prove in use much stronger and will be cheaper to fabricate and assemble.

Each of the semi-circular barrel sections A is provided at its opposite longitudinal edges with an inwardly rolled or crimped portion 15 and an outwardly rolled or crimped portion 16, which extend the length or depth of the barrel and terminate as at 17, at a point slightly below the ends 18 of the sections.

As clearly appears in the drawings, these rolled or crimped portions 15 and 16 are composed of double thickness of the material from which the barrel sections are constructed, the barrel material being bent backwardly and inwardly upon itself, as at 19 to provide for this reinforcement.

It will be seen that the inwardly rolled or crimped edges of the container sections are so formed as to be approximately U-shaped in horizontal section, as more clearly appears in Fig. 4 of the drawings, and that the inwardly rolled edge of one container section interlocks with the outwardly rolled edge of the other container section. These interlocking edges are constructed in such a manner that the edges of the barrel sections will easily slide longitudinally or in a telescoping manner, one into the other. The joint between the interlocking edges of the sections is not so tight as to make it difficult to slide the sections longitudinally or in a telescoping manner, as described.

The ends 18 of the container, before referred to, are slightly above the ends 17 of the inwardly rolled edges of the section and are composed of a double thickness of the material of which the container is constructed, as clearly appears at 20, the double thickness of the material being obtained by bending the section ends inwardly and downwardly upon the sections as appears at 21. The thickness of the container section ends is then bent inwardly at right angles, as at

22, to form an inwardly extending shoulder or flange. This construction materially strengthens the ends of the sections and adds rigidity to them.

5 To add further strength and rigidity to the container sections, I have provided them with a series of horizontal corrugations 23, which taper inwardly at their ends, as at 24, to disappear into the container sections adjacent the rolled or crimped edges thereof. Attention is directed to the fact that the inwardly bent portion 19 of the crimped or rolled edges of the sections extend backwardly to the point 25, so as to meet the 10 tapered ends 24 of the corrugations 23, to assure strength to the sections at this point.

Referring now to the container heads, it will be seen that the heads B are circular in form having a bottom 26 with a surrounding wall 27, which is tapered slightly outward and is provided with an outwardly extending top or flange 28, which terminates in a downwardly extending end 29, which is approximately in horizontal separated relation to the wall 27 of the head. The downwardly extending portion or outer wall of the head terminates in an outwardly extending flange 30, which is composed of a double thickness of material, as clearly appears. It 25 will also be readily apparent that there is a space 31 between the inner and outer walls 27 and 29 of the head.

With the container sections 20 in an assembled position, the head B is placed upon the upper end 18 of the sections, the inwardly turned flange or shoulder 22 and also a portion of the inner locking edges of the sections extending into the space 31, between the inner and outer walls of the head. 40 The shoulder or flange 22 of the sections abut the portion 28 of the head and support the same upon the sections. In placing the head B upon the ends of the sections, it will be seen that the interlocking edges of the 45 sections have been compressed as clearly appears in Fig. 5 of the drawings. The compressing of the interlocking edges at this point more securely locks the sections together.

50 To securely lock the heads in place upon the container sections, the inner wall 27 of the head is crimped outwardly and upwardly under the flange or shoulder 22 of the sections, as designated at 32.

55 It will be readily understood that one head is first crimped or locked in position and that the container is then loaded and the other head locked in position.

The outward crimp of the inner wall 27 60 of the head B completely encircles the head with the exception of the points adjacent the interlocking edges of the sections. It will, of course, be impossible to expand the head outwardly at this point.

65 Attention is directed to the fact that when

the heads are in place upon the sections, the container has great strength adjacent its ends as there are three thicknesses of material, viz, the outer wall 29 of the heads; the wall of the sections; and the inwardly and downwardly bent portion 21 of the section ends.

Great strength is given to the container at the point where the sections interlock inasmuch as at these longitudinal connections there are eight thicknesses of material, while 75 at the points where the interlocking edges are within the head, there are ten thicknesses of material, as clearly appears in Figs. 3, 4, 5 and 6 of the drawings.

As previously mentioned, it is essential 80 that the several parts of the container shall stack to enable tonnage to be loaded in a freight car, or the like. In Figs. 10 and 11 the nesting of the heads B and the sections A is clearly shown. No particular or specific description of these figures is thought to be necessary, for it is obvious from the drawings that the several parts stack nicely.

It is essential that the heads of the container be securely locked in place so as to 90 remain in place despite heavy handling when loaded. In the preferred form of my invention, the head is crimped outwardly throughout its periphery with the exception of the points immediately adjacent the interlocking 95 edges of the sections.

In Fig. 9 I have shown a modified form of locking the heads in place, which may be utilized, if desired. In the modified form, the inner wall 27 is crimped or bent upwardly under the flange 22 of the section ends at a plurality of separated points, as at 33. In crimping the head at a plurality of separated points, the head could be more easily removed from the container than would be the case were it bent outwardly throughout its periphery.

Attention is directed to the fact that when the container is in its assembled form, as shown in Fig. 1, of the drawings, it can be 110 rolled upon its side and when it is so moved, the outstanding beads or flanges 30 of the heads will act as hoops as they stand slightly beyond the horizontal corrugations 23 of the container sections, as clearly appears in 115 Figs. 3 and 5 of the drawings.

A careful examination of the drawings will also disclose that there are no sharp cutting edges to any parts of the container. The ends of the sections are provided with 120 inwardly extending shoulders 22, which are composed of a double thickness of metal and, therefore, present no cutting edges. This is important for the reason that when the sections are assembled pressure must be 125 exerted upon their upper ends to slide them into longitudinal interlocking engagement. The side edges of the containers present no cutting edges for the reason at these points 130 the sections are likewise composed of a dou-

ble thickness of metal. The heads of the container have a double thickness of metal where the material ends in the outwardly extending flange 30, so that there are no sharp 5 cutting edges to any part of the heads.

I have previously mentioned that the heads are locked in place by crimping their inner walls outwardly. This crimping or extending may be accomplished in any desired 10 manner and can readily be brought about by the crimping tool, which is disclosed in my application Serial No. 651,077, filed in the Patent Office July 12, 1923. A slight modification of the tool shown in this application 15 would produce the crimps shown in the modified form of locking the heads in, as appears in Fig. 9 of the drawing of the present application.

With the container heads constructed in 20 the manner described, there is provided for the trade a large amount of space in which to stencil their name, the contents of the container; the address to which the contents is going or any other data which may be 25 desirable. This data is usually put on the heads by means of stenciling with paint or the like, or sometimes it is done by embossing the words into the metal. I have found that when a container is loaded there is 30 somewhat of a tendency for the head bottom to bulge outwardly and in this manner the stenciling is sometimes rubbed off or effaced. To prevent the effacing of the wording on the head, I have provided what I have 35 termed a center button or fifth leg 34. This

button is an outward bulge in the center of the head and if the container head bulges outwardly, this button will engage the floor or ground and prevent the effacing of the reading matter on the remainder of the head. 40 It will be also understood from the drawing that this outwardly projecting button 34 formed in the head B prevents the head being depressed by its contents, and hence prevents the outwardly bent portion of the 45 head being loosened in respect to the inwardly bent flanges on the ends of the two parts A.

Having thus described my invention, what I claim and desire to secure by Letters Patent is:—

A metal keg and the like having a body portion with its end turned inwardly forming a short horizontal inwardly extending flange in combination with a cover having a 55 U-shaped portion, the outer wall of the U engaging the said body portion, the inner substantially parallel wall embracing the said flange, the U having a horizontal portion resting on the outer side of said flange 60 and the vertical inward wall punched outward to form outwardly and downwardly extending portions located below the said short horizontal flange, thereby uniting the closure to the said flange, substantially as 65 shown.

In testimony whereof I hereunto affix my signature.

GEORGE EUGENE MITTINGER.
